UNITED STATES PATENT OFFICE

110,126

DESIGN FOR A TELEPRINTER CABINET

Victor Weidner, Port Washington, N. Y., assignor
to The Western Union Telegraph Company,
New York, N. Y., a corporation of New York

Application April 15, 1938, Serial No. 76,544

Term of patent 14 years

To all whom it may concern:

Be it known that I, Victor Weidner, a citizen of the United States, residing at Port Washington, in the county of Nassau and State of New York, have invented a new, original, and ornamental Design for a Teleprinter Cabinet, of which the following is a specification, reference being had to the accompanying drawing, forming part thereof.

The figure is a perspective view of a teleprinter

cabinet, showing my new design. The rear wall of the cabinet is substantially flat, except that the upper portion thereof is curved forwardly to merge with the top of the cabinet as indicated in the figure.

I claim:

The ornamental design for a teleprinter cabinet, as shown and described.

VICTOR WEIDNER.
